US00D476097S

(12) **United States Design Patent** (10) Patent No.: **US D476,097 S**
(45) Date of Patent: ** Jun. 17, 2003

(54) **INTEGRATED GRAB RAIL AND MAP LIGHT**

Primary Examiner—Marcus A. Jackson

(75) Inventor: **Haithi Yan**, Columbus, OH (US)

(74) Attorney, Agent, or Firm—Rankin, Hill, Porter & Clark LLP

(73) Assignee: **Honda Giken Kogyo Kabushiki Kaisha**, Tokyo (JP)

(57) **CLAIM**

(**) Term: **14 Years**

The ornamental design for an integrated grab rail and map light, as shown and described.

(21) Appl. No.: **29/153,212**

DESCRIPTION

(22) Filed: **Jan. 2, 2002**

FIG. 1 is a perspective view showing a first embodiment of the integrated grab rail and map light according to the present invention.

(51) LOC (7) Cl. **26-04**

FIG. 2 is an elevational view of a front side of the first embodiment of the design, the rear side being identical thereto.

(52) U.S. Cl. **D26/28**

FIG. 3 is an elevational view of a right end of the first embodiment.

(58) Field of Search D26/24-36, 37-50;
362/157, 158, 171, 172, 173, 183-208

FIG. 4 is a top plan view of the first embodiment;

(56) **References Cited**

FIG. 5 is an elevational view of a left end of the first embodiment;

U.S. PATENT DOCUMENTS

FIG. 6 is a perspective view showing a second embodiment of the integrated grab rail and map light according to the present invention.
